HIS ATTORNEY.

UNITED STATES PATENT OFFICE

CHARLES R. VOLZ, OF WALNUT CREEK, CALIFORNIA

PROTECTOR

Application filed December 19, 1927. Serial No. 240,951.

My invention relates to guards for protecting portions of the body from bruising or other injury, and particularly to guards for players of football and other athletic sports.

5 An object of my invention is to provide a guard or protector which will shield the region it is desired to guard from the effect of a blow or pressure.

Another object of my invention is to provide 10 a guard which combines lightness and comfort to the wearer with full protection.

A further object is to provide a guard which is rigid but which will not be liable to inflict injury to an opposing player.

15 My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

Referring to the drawings:

25 Fig. 1 is a front elevation of a thigh protector embodying my invention; and Figs. 2 and 3 are vertical and horizontal sectional views respectively of the same device, the planes of section being on the lines 2—2 of Fig. 1 in Fig. 2, and 3—3 of Fig. 1 in Fig. 3. More clearly to indicate the application of my device, the body of the wearer is shown by dotted lines in Figs. 1 and 3.

Protective armor has been worn by athletes since the time of the gladiators; and is familiar to us today in the shoulder guards of football players, the shin guards of hockey and baseball players, and the chest protectors worn by baseball catchers. In general, the 40 function of such armor is to cushion the impact of the blow and distribute its force over a relatively large area. Favorite materials for such guards are sole-leather and padding. A protector of such material, if it is to accomplish its purpose, is heavy and uncomfortable, and will usually cause chafing. Moreover, if the parts to be protected have 45 previously been injured, even the decreased shock transmitted thru the guard may be 50 painful or injurious. The protector of my

invention has none of these disadvantages.

Broadly considered, my invention comprises a padded frame supported by the body-area surrounding the region it is desired to protect. Arched over this frame, and secured thereto at its opposite edges, is the guard or shield proper, shield and frame being in contact only at the edges where they join. A suitable harness holds the protector in place.

55 For the purpose of detailed description I have shown a thigh protector as embodying my invention in its preferred form. The painful affliction known to athletes as "charley-horse" often results from bruises to the 60 belly of the long muscles between the hip and the knee. The protector described is designed to prevent this type of injury, but it is obvious that the same principles of construction may be used in protectors designed 65 for almost any part of the body.

70 As illustrated, a pad 4, which may be of felt, rests against the leg 6 of the wearer. Over the felt lies a ring-like frame, preferably of vulcanized sheet fiber, comprising the 75 yokes 7 which conveniently may be integral with side members 8. The whole frame surrounds the region 9 which is to be protected and is complementary to the adjacent body area 11. The pad 4 may cover the entire 80 surface as shown, since the felt is so weak in tension that it will not transmit stresses to the protected area or may be cut away at the center to prevent any contact with the protected region.

85 Arched over the frame is the shield 12. I prefer to make the shield of vulcanized sheet fiber, but other materials may be used if desired. It will be noted that shield and frame are formed without sharp corners which 90 might cause injury. Vulcanized fiber is preferred since it combines a desirable limited degree of flexibility with a general rigidity.

95 The rivets 13 offer a convenient method of securing the edges of the shield to the frame, and at the same time hold the pad in place and attach a harness for retaining the protector in position.

100 The harness in the present instance comprises a pair of elastic fabric bands 14 adapt-

ed to surround the leg of the wearer, and a pair of straps 16 by which the protector is supported from the belt 17.

The protector described weighs less than 14 ounces including the harness. It affords complete protection to the area within the frame; is fully ventilated, permitting free transpiration and lessening the liability of chafing; and distributes the shocks over a relatively large area of relatively insensitive tissue adjacent the protected area. Because of the elasticity of the protector as a whole it is incapable of inflicting injury to an opposing player.

15 I claim:

1. A protector comprising a rigid unyielding open frame adapted to circumscribe the area of the body to be protected and to bear on the body around said area, and a curved unyielding shield fixed to the frame and overlying the protected area and frame in spaced relation to said frame intermediate its side edges and adapted to receive a blow and distribute it over the portion of the body 25 against which the open frame bears.

2. A protector comprising a rigid unyielding open frame adapted to circumscribe the area of the body to be protected and a curved unyielding shield fixed to the frame and overlying the protected area and frame in spaced relation to said frame intermediate its side edges and adapted to receive a blow and distribute it over the portion of the body against 30 which the open frame bears, said frame being continuous and entirely surrounding the area 35 to be protected.

In testimony whereof, I have hereunto set my hand.

CHARLES R. VOLZ.
